UNITED STATES PATENT OFFICE

VERNON MARTIN, OF PARIS, ONTARIO, CANADA, ASSIGNOR TO WALKER PRESS LIMITED,
OF PARIS, ONTARIO, CANADA

DESIGN FOR A BRIDGE TALLY

Application filed November 11, 1932. Serial No. 45,880. Term of patent 7 years.

To all whom it may concern:

Be it known that I, VERNON MARTIN, a subject of the King of Great Britain, residing at the town of Paris, in the county of Brant, Province of Ontario, Canada, have invented a new, original, and ornamental Design for a Bridge Tally, of which the following is a specification, reference being had to the accompanying drawings, forming part thereof, in which—

Fig. 1 is a view of the outside of the folded tally, slightly in perspective, showing my new design, and

Fig. 2 is a view of the inside of the complete tally.

I claim:

The ornamental design for a bridge tally, as shown.

VERNON MARTIN.
